(57) **CLAIM**

The ornamental design for a bezel for a document validator, as shown and described.

DESCRIPTION

FIG. 1 is a front view of a bezel for a document validator according to my new design;

FIG. 2 is a rear view thereof;

FIG. 3 is a right side view thereof;

FIG. 4 is a left side view thereof;

FIG. 5 is a plan view thereof;

FIG. 6 is a bottom view thereof;

FIG. 7 is a front perspective view thereof;

FIG. 8 is a rear perspective view thereof; and,

FIG. 9 is a front perspective view of the bezel attached to a document validator.

The broken line showing of environment is for illustrative purposes only and forms no part of the claimed design.
